GARMENT

George K. Manus, Los Angeles, Calif.

Application February 16, 1934, Serial No. 711,536

4 Claims. (Cl. 2—93)

Broadly considered this invention pertains to wearing apparel.

An object of the invention is to provide, in combination with other improved features, a coat which will ventilate the skin of the wearer in an efficient manner, yet without any injurious direct exposure of the surface of the body to the external atmosphere.

Another object of the invention is to provide a garment of the above stated character which will adjust itself to individuals whose bodies differ considerably in size, and which will, therefore, enable the clothier to reduce the number of sizes necessarily carried in stock to fit all sizes of customers. This feature of the invention also possesses the advantage of making it less needful to alter the cut of the garment to secure a fit thereof upon individuals having inequalities of physical development. It also makes the article particularly useful as a child's garment, since it prolongs the period thruout which it can be worn by a child before being outgrown. Furthermore, this capacity of the garment for conforming itself to differently shaped bodies also makes it more comfortable to the wearer, particularly during active muscular exercises, as for example in physical culture and athletic contests wherein the musculature of the body undergoes rapid changes in its external contour.

Both men and women who have a taste for out-of-door sports will find this garment comfortable, durable, and satisfactory.

The durability of the garment is increased by reason of the fact that it is constructed in such a manner as to conform, without much strain between its various parts, to the various changing postures of the body of the wearer, even when he or she is participating in the vigorous exercises above alluded to.

While the invention has been illustrated as embodied in a man's coat, yet it is to be understood that its usefulness is not limited to such a garment, but that other clothing, coming within the scope of the appended claims, may be fabricated according to the principles of the invention.

Referring to the accompanying drawing, which illustrates what is at present deemed to be a preferred embodiment of the invention,

Fig. 1 is a front view of the complete garment; Fig. 2 is a back view thereof; Fig. 3 is a transverse section on line 3—3 of Fig. 2; Fig. 4 is a view of the patterns composing the left and right hand halves of the V-back; these two halves being shown adjacent to each other to in-

dicate the manner in which they join; Fig. 5 is a back view of the garment indicating the manner in which the parts seen in the view are assembled; Fig. 6 shows the garment adapted to a broad shouldered man; and Fig. 7 is a view of the coat shown in Fig. 6 adapted to a man of more slender build.

Referring in detail to the drawing, the invention is shown as incorporated into a coat structure having right and left back side portions 7 and 8 which have between them a recess or space 9. This cut-away portion tapers from above downwardly, being desirably triangular, and it extends from the edge of the neck portion of the coat down to approximately the waist line.

As a means for covering the underclothing of the wearer beneath said cut-away part or space 9, the garment is furnished with a back flap 10 which also diminishes in width from above downwardly, but which is of sufficient length and breadth not only to cover the space 9 but also to overlie to a considerable extent the portions of the main garment adjacent to said space 9.

The wide upper end of flap 10 is at each side attached along the shoulder seams to the body portion of the garment. Along the greater extent of both of its side edge portions said flap 10 is in an entirely detached relation to the underlying portions of the main garment. This arrangement is provided in order that the indirect body ventilation, freedom of movement, and other improved features of the invention be attained.

As shown in Fig. 4 said overlying flap 10 is preferably formed in two identical approximately triangular halves 10a and 10b, which are sewed together along the edge 10c which is intermediate the other two sides of the triangle.

The overlaps 15 and 16 between the side portions of the flap 10 and the underlying margins of the main portion of the garment are sufficient to insure that the garment will at all times form a complete covering for the skin and undergarment of the trunk of the body of the wearer, even tho the width of each of these overlaps may vary considerably during the performance of any exercise which greatly varies the posture of the body of the wearer. The same garment will also adapt itself to considerable differences in size and build of body, as contrastively illustrated in Figs. 6 and 7. In these views two garments of the same size are shown, the garment of Fig. 6 being fitted to a broadly built man and that of Fig. 7 being fitted to a slender man.

Fig. 7 being worn by a man of more slight build.

Owing to the fact that the cut away space is triangular and tapers downwardly to an apex which is located nearer the waist line, the flap 10 may be made narrow at its lower end, and may even be tapered to substantially a point, as shown, thus economizing material. This construction takes advantage of the fact twisting movements of the wearer's body will displace the triangular flap 10 the least near the waist line.

Referring to certain details of construction, as shown in Fig. 5, at its inner side the left coat back section 8 is notched at $8x$ and the part 17 of the fabric below the notch is folded inwardly to an extent substantially equal to the depth of said notch as best shown in section in Fig. 3, it being understood that the wide hem 17a thus formed will be held in place by suitable stitching. By this construction the line of overlap in the tail portion of the coat is properly centered. Also by cutting out a portion of the garment at $8x$ the tailor avoids bringing any part of left back section 8 into view above the belt at the right hand side of the mid-width of the garment.

The lower portion of the flap 10 is stitched to the inner side of the belt at 18. For a short distance above the belt said flap is provided on the right side with stitching 19 to secure it to the right back section 7. On the left hand side stitchings 20 and 20a are provided which aid in securing together the hemmed portion 17a, belt, and back coat section 8. The back sections 7 and 8 may readily be stitched together where they overlap between the notch $8x$ and the apex of the triangular space which is covered only by the flap 10.

It will be seen that the cut-away portion or recess 9 extends completely thru the back portion of the garment and opens out at an edge thereof. It will also be noted that the flap 10 is the only part of the garment that spans said cut away portion.

I claim:

1. A coat or the like having a pair of back sections which are separated by a space throughout their upper portions and which meet and are secured together below said space, one of said back sections having a notch in its inner edge below said space, the material of said notched section being folded under below said notch to an extent substantially equal to the depth of said notch, thereby causing the folded edge of the folded part substantially to aline with the mid-width of the back of the garment; and a flap to cover said space together with the marginal portions

of said back sections along each side of said space and therebelow, said flap being in a detached relation to said back sections along each of its side edges, the upper portion of said flap being attached to the adjacent parts of said back sections, there being, adjacent to the aforesaid notch, attaching means which secures together the adjacent edge portions of said back sections. 5

2. A coat or the like having a pair of back sections which are separated by a space throughout their upper portions and which meet and are secured together below said space, said space being shaped as a triangle having its apex directed downwardly, one of said back sections having a notch $8x$ in its inner edge below said space, said back sections overlapping each other throughout the distance between said notch and space, the material of the notched section being folded back below said notch to a sufficient extent to cause the folded edge of the folded part substantially 10 to aline with the mid-width of the garment, a fabric layer to cover said space, and means to fasten said back sections together below said space. 15

3. A coat or the like having a triangularly cut 25 away portion in its back extending therethru with the apex of the triangular portion directed downwardly from its neck portion, and terminating in the medial line of the body, a belt adjacent the lower end of said cut away portion, a flap 30 having side portions which in a disconnected manner widely overlies the right and left marginal portions of the coat at each side of its said cut away portion, the lower end of said flap being attached to said belt, one of said right and 35 left marginal portions of the coat having a notch in its inner edge below said cut away portion, and stitching uniting the edges of said notch to the portion which it overlies and to said belt.

4. A coat or the like having a triangularly cut 40 away portion in its back extending therethru with the apex of said triangular portion directed downwardly from its neck portion and terminating at substantially the medial line of the body, a triangular flap having upper portions fastened 45 to the coat and having side portions which in a disconnected manner overlie the right and left marginal portions of the coat at each side of said cut away portion, the apex of said triangular flap being located at a point spaced downwardly below the said apex of said cut away portion, the apex portion of said flap being secured to the coat below the apex of said cut away portion. 50
